UNITED STATES PATENT OFFICE.

ALFRED B. ROSEBOOM, OF CHICAGO, ILLINOIS.

DESIGN FOR SHEET METAL.

Application filed April 15, 1922. Serial No. 1,783. Term of patent 3½ years.

To all whom it may concern:

Be it known that I, ALFRED B. ROSEBOOM, a citizen of the United States, residing at Chicago, in the county of Cook and State of Illinois, have invented a new, original, and ornamental Design for Sheet Metal, of which the following is a specification, reference being had to the accompanying drawing particularly thereof.

The figure is a perspective view of a section of sheet metal showing my new design.

The design is used in connection with casseroles and other metal household receptacles and is made and sold as a separate article of manufacture.

I claim:

The ornamental design for sheet metal, substantially as shown.

ALFRED B. ROSEBOOM.
